Primary Examiner—Susan Bennett Hattan*(74) Attorney, Agent, or Firm*—Schmeiser, Olsen & Watts,
LLP(57) **CLAIM**

The ornamental design for a dispenser cap, as shown and described.

DESCRIPTION

FIG. 1 is a perspective view of a dispenser cap of my invention.

FIG. 2 is a top view thereof.

FIG. 3 is a posterior angled perspective view thereof, with an over-cap in an open position.

FIG. 4: is an anterior angled perspective view thereof, with the over-cap in an open position; and,

FIG. 5: is a front elevational view thereof.

Broken lines, where shown, depict environmental subject matter only and form no part of the claimed design.
